UNITED STATES PATENT OFFICE.

HENRY E. WAITE, OF NEWTON, MASSACHUSETTS.

MAIL-MARKING APPARATUS.

SPECIFICATION forming part of Letters Patent No. 752,132, dated February 16, 1904.

Application filed July 15, 1901. Serial No. 68,285. (No model.)

To all whom it may concern:

Be it known that I, HENRY E. WAITE, of Newton, in the county of Middlesex and State of Massachusetts, have invented certain new and useful Improvements in Mail-Marking Apparatus, of which the following is a specification.

This invention relates to apparatus for stamp-cancelling and postmarking mail-matter in post-offices; and its object is to save time and labor on the part of the post-office attendants and to facilitate the marking of the mail which is deposited by the public in the office.

Much time and labor have already been saved by the introduction into post-offices of machines for automatically marking the letters in place of the method of marking them by hand-stamps which formerly prevailed to the exclusion of other methods, such machines operating either by having the letters fed to them by an attendant, who stands at a table bearing the unfaced letters and feeds the letters one by one properly faced into the machine, so that each will receive the postmark of the outgoing office on the side bearing the stamp and the address, or by receiving into a feed-receptacle on the machine a stack of letters already faced, the machine taking the letters one by one automatically from the face of the stack and marking them. Both of these methods involve the collection of the letters by the post-office attendants from the places where they have been deposited by the public and the facing of the letters prior to depositing them in the mail-marking machine.

My present invention dispenses with a large part or the whole of the labor of attendance heretofore required for these operations by the provision of means whereby the public is enabled to deposit letters directly in the mail-marking machines and have the letters properly marked.

An embodiment of the invention is herein-after described, and illustrated in the accompanying drawings, in which—

Figure 1 represents a vertical sectional view of a mail-marking apparatus constructed in accordance with my invention. Fig. 2 represents an elevation of the apparatus looking from the inner or office side of the partition shown in Fig. 1. Fig. 3 represents a horizon-

tal section on the line 3 3 of Fig. 1. Fig. 4 represents an enlargement of parts shown in Fig. 1. Fig. 5 represents a detail view showing the detachable operating-handle and its shaft separated.

The same reference characters indicate the same parts in all the figures.

Referring to the drawings, 40 represents an inclosure, room, or office designed to be occupied by the postal attendants and from which the public is excluded by a wall or barrier 41. On the outer side of this barrier is a space 42, which may be a room devoted to the public or may be merely the space on the outside of the post-office building. The barrier 41 is shown in the form of a partition extending from the floor 43 of the office 40 to the roof or ceiling 44 thereof, and including the walls of a pocket or recess 45. At the rear lower edge of said recess is a slot 46, designed for the deposit of letters by the public to be received and marked in the office 40 on the inside of said partition and constituting a mailing-channel extending through said partition. Below said slot are parallel walls 47 47, constituting a guide or chute through which the letters fall in a vertical position upon an endless-belt carrier 7, by which they are advanced edgewise in the direction of the arrow in Fig. 2. This carrier passes over idle pulleys 48 48 and around a pulley 49 on a driving-shaft 50, whereby the belt is continuously driven. Above the carrying-belt, at a convenient distance above the slot 46 in the direction of the advance of the letters, are located marking or imprinting devices, represented by the casings 51 52 and the disks 25 25, on opposite sides of the letter-path for postmarking and stamp-cancelling the letters. These marking devices may be of any desired character already known in the art.

The marking devices are driven by two shafts 1 2, connected to each other by gears 3 4 and rotated by means of bevel-gears 53 54 from the driving-shaft 50. After the letters have been marked they are carried by the belt 7 and the impulse of the marking devices into engagement with a rotary stacker 55, which stacks the letters in a stacking-trough 56. From the latter repository the letters have

merely to be removed by the post-office attendants and sent to their destinations. The stacker 55 is represented as driven by a belt 57, which passes around a pulley 58 on its 5 shaft and a pulley 59 on the shaft 1.

The operating parts of the machine may be driven in any suitable manner. In offices where the business is large in volume it will generally be preferable to run the machine continuously by means of a motor. I have shown arrangements for this purpose, consisting of an electric motor 60, having a pulley 61 on its shaft adapted to be connected, by means of a belt, with a pulley 62 on the shaft 50 of the 15 machine. An alternative means of propulsion is the crank 63, fixed to the shaft 50 and located outside of the partition 41, so as to be operated by the person depositing the letter. The crank is removably fixed to the shaft, as 20 indicated in Fig. 5, and will be removed when the machine is run by motor-power. Conversely, the belt will preferably be removed when the crank is in place, as indicated in the drawings.

25 Suitable directions as to the manner in which to deposit a letter in order to have it properly marked will be displayed to the public, and even though these directions be disregarded in some instances the proportion of 30 letters properly marked will be sufficient to greatly lighten the former labor of attendance in post-offices. Mismarked letters may be quickly sorted out and marked over again in a proper manner by the post-office attendants.

35 The inner wall of the recess 45 is represented as a swinging flap 64, hinged at 65 along its upper edge and adapted to be moved by a cam-lever 66, so as to assume either one of two positions represented by full and dotted lines, respectively, in Fig. 4. By this means the slot 46 may be opened either to the public side of the partition or to the office side. In the latter case the public will be excluded.

45 It will be seen that the path of the letter upon being deposited in the slot 46 is in a horizontal direction and parallel or longitudinal with respect to the partition 41. Such an arrangement avoids projecting the length of the 50 machine out into the post-office in a direction transverse to the partition.

In addition to the advantages above pointed out it should be particularly noted that the letter opening or chute is open either to the 55 public or to the employees. Hence letters may be readily inserted. In small offices where the quantity of mail is such as to make it unnecessary to use the power device the manually-operated device may be used, and 60 the movement thereof will carry the deposited letters out of alinement with the letter-opening or out of the path of movement of the letter next deposited. This would be the case even if more than a single letter were deposited at the same time, the depositing of the

letter not affecting the movement of the marking mechanism in any respect. In cities where the quantity of mail-matter is large and the power mechanism is used the conveyer will remove the letters deposited as rapidly as 70 they pass through the letter-opening, thus permitting of a rapid feeding of letters to and through the letter-opening and to the conveyer and without liability of deranging the mechanism in any manner, and in this respect 75 the feeding of more than a single letter at the same time will not affect the operation of the device, the number being introduced being controlled by the ability of the chute to pass them. It will therefore be obvious that with 80 the apparatus described it is possible to cope with either a large or small amount of deposited mail, the capacity being determined only by the size of the opening and permitting the feeding of letters continuously, there 85 being no obstructing means which would delay the feeding of the letters.

I claim—

1. A mail-marking apparatus comprising an office having a wall or barrier provided with a normally unobstructed letter-opening, letter-advancing means within the office for moving letters deposited through said opening out of alinement with said opening, and means to mark the letters received from said 95 letter-advancing means.

2. The combination of a wall or barrier, a letter-marking machine on one side of said barrier, a letter-opening in said barrier out of alinement with the marking-machine, and 100 means for moving the letter from said opening to the marking-machine as it is deposited, whereby the opening is maintained unobstructed for the passage of letters.

3. A mail-marking apparatus comprising 105 an office having a wall or barrier provided with a letter-opening, mechanism within the office for marking letters deposited in said opening, said mechanism being out of alinement with said letter-opening, and means accessible from the outer side of said barrier and non-obstructive of said opening for operating said mechanism.

4. A mail-marking apparatus comprising an office having a wall or barrier provided 115 with a letter-opening, mechanism within the office for marking letters deposited in said opening, said mechanism being out of alinement with said letter-opening, a motor for operating said mechanism, and means accessible from the outer side of said barrier for operating said mechanism, said means having provisions for detachment from operative position.

5. A mail-marking apparatus comprising 125 an office having a wall or barrier provided with a letter-opening, mechanism within the office for marking the letters deposited in said opening, said mechanism being out of alinement with said letter-opening, and means con- 130

trollable from within the office for obstructing or exposing said opening.

6. A mail-marking apparatus comprising an office having a wall or barrier, a mailing chute accessible from both the outer and inner sides of said barrier, mechanism within the office for marking letters deposited in said chute, said mechanism being out of alinement with said chute, and means movable into or out of a position obstructing said chute from the outside.

7. A mail-marking apparatus comprising an office having a wall or barrier, a mailing-chute-accessible from both the outer and inner sides of said barrier, mechanism within the office for marking letters deposited in said chute, said mechanism being out of alinement with said chute, and a chute-controlling device

movable into position to obstruct the chute either from the outer side or the inner side of said partition, leaving it exposed from the opposite side.

8. The combination of a wall or barrier having a letter-opening, mail-marking mechanism located on one side of said barrier, means for moving the deposited letters to said mechanism, and means for varying the relative positions of said barrier and opening to permit of the opening receiving letters from one side or the other of the barrier.

In testimony whereof I have affixed my signature in presence of two witnesses.

HENRY E. WAITE.
